 corporation of New York

Application August 12, 1952, Serial No. 303,900

17 Claims. (Cl. 1—49)

1

The present invention relates to spring operated type staplers, tackers and similar devices.

Generally, devices of this character comprise a body, an operating handle pivoted to the body, a spring pressed driver blade which is actuated and abruptly released by movement of the handle, and a staple magazine mounted in the body for feeding staples to be driven by the driver blades.

An object of this invention is to provide improved mechanism for actuation of the driver blade by the operating handle.

A further object of the invention is to provide a mechanism of this character in which the staple driving movement of the spring pressed driver blade is obtained by an improved system of linkage actuated by the operating handle.

Another object of the invention is to provide improved stop means for limiting the travel of the driver blade after a staple has been driven.

Still another object of the invention is the provision of improved stop means of this character in which one of the stop members may conveniently be hardened to obtain longer wear without hardening the entire body of the device.

Yet another object of this invention is to provide a tacker of the character described so constructed as to obtain good leverage with small handle movement and in which the links and levers interconnecting the handle with the plunger operated member do not include any links or levers that are too long but which are of strong and rugged construction and which will withstand continued use for long periods.

Still another object of this invention is to provide a tacker of the character described so constructed that when the handle goes down, a trigger is powered to pull upwardly on a plunger, the design being such that the trigger will leave the plunger at a predetermined point and a spring will depress the plunger. On the way down the plunger pushes the trigger back so as to by-pass the trigger. Spring means are provided to push the trigger forwardly to reengage the plunger. When the handle is released, the trigger comes down and is cammed backward to by-pass the plunger. The trigger has a kidney shaped hole through which the pivot for the trigger passes, the hole being so arranged so as to keep the trigger in its forward position except when the trigger has to go back as it is cammed to by-pass the plunger.

Yet another object of this invention is to provide a tacker of the character described, provided with a hardened front cover formed with slots in its front wall and a staple magazine hav-

2

ing lugs at its front end received in said slots to aid in supporting the front end of the magazine and to withstand continual pounding each time the plunger descends on the spring action.

Still another object of this invention is to provide a strong, rugged, durable and compact tacker of the character described, which shall be relatively inexpensive to manufacture, easy to assemble, which shall be easy to manipulate, and yet practical and efficient to a high degree in use.

Still a further object of this invention is to provide a tacker of the character described in which the nosepiece has apertured ears serving as bearings for the pin on which the lever of the plunger actuating mechanism is mounted. The nose piece may be hardened thereby supplying long wearing bearings for said pivot pin.

Yet another object of this invention is to provide in a device of the character described, a body open at its lower end, a staple magazine mounted in the bottom of the body and pivoted at its rear end on a pin removably mounted on the body, and said staple magazine having forwardly projecting lugs at its front end received in slots in the front wall of the front nosepiece. With such construction removal of said pivot pin will permit the entire staple magazine to be readily withdrawn from the tacker upon merely moving the staple magazine rearwardly sufficiently to disengage said lugs from said slots.

Yet a further object of this invention is to provide in a tacker of the character described, a shock absorber riveted to the underside of the handle, said shock absorber comprising a rectangular pad of rubber-like material and a rectangular plate at the underside of said pad, the arrangement being such that upon depressing the handle, said rectangular plate will contact the top edges of the body of the tacker to serve as a shock absorbing stop for the handle.

Other and further objects will become apparent upon reading the following specification together with the accompanying drawing forming a part hereof.

The invention accordingly consists in the features of construction, combinations of elements, and arrangement of parts, which will be exemplified in the construction hereinafter described, and of which the scope of invention will be indicated in the following claims.

In the drawings:
 Fig. 1 is a side elevational view of an embodiment of the invention, partly broken away, with operating handle in its normal position;

Fig. 2 is a fragmentary view similar to Fig. 1, 55 showing the operating handle partially depressed

just before release of the spring pressed driver blade;

Fig. 3 is a fragmentary view similar to Figs. 1 and 2 showing the staple driving mechanism just before the operating handle reaches its fully raised position;

Fig. 4 is an end sectional view taken along the line 4—4 of Fig. 1, looking in the direction of the arrows;

Fig. 5 is a plan sectional view taken along the line 5—5 of Fig. 2;

Fig. 6 is a plan sectional view taken along the line 6—6 of Fig. 1;

Fig. 7 is a plan sectional view taken along the line 7—7 of Fig. 12;

Figs. 8, 9, 10 and 11 are sectional views of the linkage mechanism taken along the lines 9—9; 10—10; and 11—11 of Fig. 1, in each instance looking in the direction of the arrows;

Fig. 12 is a fragmentary side elevational view partly broken away;

Fig. 13 is an end view, partly broken away;

Fig. 14 is a side elevational view of a tacker embodying the invention and illustrating a modified construction;

Fig. 15 is a cross sectional view taken on the line 15—15 of Fig. 14;

Fig. 16 is a cross sectional view taken on the line 16—16 of Fig. 14;

Fig. 17 is a cross sectional view taken on the line 17—17 of Fig. 14;

Fig. 18 is a cross sectional view taken on the line 18—18 of Fig. 14 but with the handle completely pressed down.

Referring now to the drawing, 10 designates a spring actuated type of tacker embodying the invention. The same comprises a body 11 comprising a pair of similar, symmetrically disposed parts 12 having meeting edges 14 along a longitudinal vertical plane through the middle of the body. The body is formed with a hand hole 15. It is open at the bottom and at its front end and at the forward portion of its upper end. Each of the body portions 12 has a side wall 16 from which extend inwardly, curved portions 17 (Fig. 6) forming said hand hole 15. At the lower end of each of the side walls 16 is a longitudinal bottom edge 18. The side walls 16 have rear ends 19. The upper portion of the rear end of the said walls 16 and the top portions thereof are curved as at 20 meeting along the meeting plane 14 (Fig. 6). At their forward ends (Fig. 5), side walls 16 are formed with vertical shoulders 21 from which extend forwardly side walls 22 spaced further apart than side walls 16.

The side walls 22 have forward edges 23 (Fig. 5). The shoulder 21 (Fig. 2) has an intermediate semi-circular shoulder portion 21a. At the axis of shoulder portions 21, side walls 22 are formed with aligned through-openings 24. The wall portions 20 are upwardly curved as at 20a at their forward ends. Extending from the upper ends of walls 20a are forwardly and upwardly inclined edges 25 merging with a downwardly curved edge 26 from which extend downwardly and forwardly, inclined edges 27. The edges 27 extend down to the forward edges 23. Forward edges 23 are formed with longitudinal grooves 23a (Fig. 1) for the purpose hereinafter appearing. The side wall portions 22 are formed adjacent the curved edges 26 with aligned through-openings 28.

The side walls 22 of the body 11 are formed adjacent their forward edges 23 with square shaped notches 30 (Fig. 12) spaced above the lower edges of said side walls. Said side walls 75

22 are also formed rearwardly of the notches 30 with square shaped openings 31 aligned with said notches. Said side walls 22 are also formed adjacent the upper ends thereof with rectangular through-slots 31a, for the purpose hereinafter appearing.

Fitted over the front of the body is a front nose piece 32. Nose piece 32 may be made of hardened steel. It comprises a front wall 33 (Figs. 3 and 5) from which extend rearwardly parallel side walls or flanges 34. The front wall 33 has a bottom edge 35 aligned with the bottom edge 18 of the body. The side walls 34 have bottom edges 36 in the same plane as edges 18 and 35. The front wall 33 has a forwardly pressed substantially rectangular portion 38 for the purpose hereinafter appearing. Furthermore, said wall 33 is formed below the forwardly spaced portion 38 with a pair of parallel horizontally aligned vertical slots 39 (Fig. 5).

At the upper end of the front wall 33 is an upwardly and rearwardly inclined wall 40 contacting the inclined edges 27 of the sides 12 of the body 11 and extending about half way up said edges. Said side walls or flanges 34 contact the outer surfaces of the side walls 22 of the body. Side walls 34 are formed at their rear ends with rear edges 41 extending upwardly from the lower edges 36. The rear edges 41 extend substantially from the lower ends of the semi-circular shoulder portion 21a. Extending from edges 41 are edges 42 following the semi-circular shoulder portions 21a. Extending downwardly and forwardly of the semi-circular edges 42 are inclined edges 43 terminating adjacent the rear ends of the bottoms of the openings 31. Extending forwardly from the edges 43 are edges 44 at the level of the lower sides of the openings 31. Extending upwardly from the front ends of edges 44 are vertical edges 45 in alignment with the front edges of said openings 31. Extending from the upper ends of edges 45 are rearwardly inclined edges 46 from which extend edges 47 located around and spaced from the openings 28. Edges 47 extend down to the upper ends of the front wall 33. The upper ends of the side walls 34 thus comprise ears 48 and they are formed with openings 49 registering with the openings 28 in the side wall portions 22.

Extending through the registering openings 28, 49 is a shaft 50 riveted at its ends as shown in Fig. 4 of the drawing. The portion of the side walls 34 bounded by edges 42, 43 comprises ears 51 formed with through openings 52 registering with the openings 24 and the side wall portions 22. Extending through registering openings 24, 52 is a bolt 53. Bolt 53 has a head 54 at one end and a threaded portion 54a at its other end on which is screwed a nut 55a. Bolt 53 is removable, for the purpose hereinafter appearing.

It will now be understood that shaft 50 and bolt 53 serve to attach nose piece 32 to the front of the body.

Mounted on the body 11 is a bottom stop member 55. Said bottom stop member 55 is a metal plate and may be hardened. It is in horizontal position as shown in Figs. 1, 2 and 6. It has at its rear end wing extensions 56 passing through openings 31 of the body side walls, and resting on the lower edges of said openings and also on the edges 44 of the side walls 34 of the nose member. Said wing extensions 56 contact the lower ends of the rear edges 45. The stop member 55 also has adjacent its front end, side extensions 57 which pass through notches 30 of the side walls 22 of the body member and rest on the

lower edges of said notches. Said stop plate 55 is formed adjacent its front edge with a central shallow slot 58 forming a passage, for the purpose hereinafter appearing.

Attached onto the top surface of the bottom stop 55 is a shock absorber 60 of the same shape as member 55 and overlying the same and made of either rubber, plastic or any other suitable material to absorb shocks, and having a slot 59a similar to slot 58 and registering therewith.

Mounted on and between wall portions 22 is a top stop 61 having side extensions 62 received within the slots 31a (see Fig. 7). Top stop 61 is formed with a central opening 62a and with a plurality of downwardly pressed lips 63 arranged in a circle, for the purpose hereinafter appearing. Top stop 61 is disposed above the bottom stop 55 and its shock absorber 60.

Slidably mounted within the front of the body and between side walls 22 (Fig. 1) and adjacent the front wall of the nose piece 32, is a plunger member 65. The same comprises a plunger cup 66 made of a single sheet of metal, die cut and pressed to the shape shown in the drawing. The cup 66 has a front wall 67 from which extends rearwardly a wall 68. Extending upwardly from the rear of wall 68 is a rear wall 69. Extending rearwardly from the front wall 67 are side walls 70. The side walls 70 are formed with rearwardly extending hooks 70a having upwardly and rearwardly inclined under edges 70b located substantially midway between the front and rear ends of said side walls. Extending inwardly from the lower ends of said side walls 70 are flanges 71 (Fig. 4) contacting the underside of bottom wall 68.

It will be noted that the cup is open at its upper end. Inserted within the cup and contacting the bottom wall 68 is the lower end of a coil compression spring 72, the upper end of which contacts the underside of the top stop 61. The downwardly pressed lips 63 are received within the upper end of spring 72. Riveted to the front wall 67 as by rivet 73 is a driver blade 74 passing through the registering slots 58 and 58a in the bottom stop 55 and the shock absorber 60, respectively. The head of the rivet 73 may be moved through the recess formed by the forwardly pressed wall 38.

The front wall 67 has a forwardly pressed lip 75 contacting the upper edge of the blade 74. Also the front wall 67 has side extensions 77 received within the groove 23a and contacting the rear surface of the front wall 33. It will now be understood that the compression spring 72 presses the plunger downwardly. The driver blade 74 passes down to the lower edge of the front wall 33.

Within the bottom of the body is a staple magazine 18 of any suitable construction. However, said staple magazine 18 has side walls 79 (Fig. 5) formed at its front end with lugs 80 projecting through the slots 39 so that the hardened nose piece 32 aids in supporting the front end of the magazine. The staple magazine 18 is hinged at its rear end with a pivot pin 31 passing through registering openings in the body 11. When the bolt 53 is removed, the nose piece 32 may be swung forwardly and the staple magazine may then be swung downwardly about its pivot pin 31 for servicing or cleaning out the tacker.

Means is provided for raising and releasing the plunger 65 to drive a staple from the magazine. To this end there is pivoted on the shaft 50 a handle 85. Handle 85 has a top wall 86

from which extend side flanges 87 are formed with through openings 88 through which the shaft 50 passes. The said side flanges 87 fit over the side walls 34 of the front nose piece. The top wall 86 has a forwardly and downwardly inclined extension 89 contacting the inclined edges 21 of the side walls 22 of the frame member. The lower end of flange 89 substantially meets the upper end of flange 40. On shaft 50 and within the body is a torsion spring 91, one arm of which contacts the underside of the top wall of the handle and the other arm of which engages the back of top stop 61. Thus the torsion spring 91 tends to raise the handle.

Attached to the underside of the handle, rearwardly of the shaft 50, is a saddle 92 formed with a pair of downwardly extending apertured flanges 93 carrying a transverse pivot pin 94. Pivoted to the pivot pin 94 and disposed within the flanges 93 is a link 95. Link 95 has a pair of side walls 96 interconnected by a rear web 97. The lower ends of side walls 96 carry a transverse pivot pin 98. Side walls 16 of the body members 11 are formed with aligned openings carrying a transverse pivot pin 100 disposed below and forwardly of the pivot pin 98.

Pivoted to the pivot pin 100 is a lever 101. Lever 101 comprises side flanges 102 interconnected by a bottom web 103. Side walls 102 have upwardly and rearwardly extending arms formed with openings through which the pivot pin 93 passes. Said side walls 102 also have downwardly and forwardly inclined arms carrying a transverse pivot pin 105. Pivoted to the point pin 105 is the upper end of link 106. Link 106 has side walls 107 interconnected by front web 108. On the pivot pin 105 is a torsion spring 109 having one arm engaging the front edge of the web 103 and a second arm contacting the back of the web 108. Thus torsion spring 109 tends to swing the link 106 forwardly.

The side walls 16 of the body members 11 are formed with aligned through-openings 16a through which pass a transverse pivot pin 110. Pivoted on the pivot pin 110 is a trigger member 111. Trigger member 111 has side walls 112 interconnected by a bottom web 113. Side walls 112 are formed adjacent their rear ends with kidney shaped openings 114 through which pivot pin 110 passes. These kidney shaped openings 114 are somewhat elongated but have a notch 115 at their rear lower ends, for the purpose hereinafter appearing. The side walls 112 are in alignment with the side walls 70 of the plunger 65. Said side walls 112 have at their forward ends upwardly projecting pointed portions 116 engaging under edges 70b of the hook 70a. Said side walls 112 are formed with aligned through openings 120 (Fig. 11) rearwardly of the pointed portions 116 carrying a transverse pivot pin 119. The lower ends of the side walls 107 of the links 106 are formed with apertures 107a through which the pivot pin passes.

It will be noted that the torsion spring 109 normally tends to press the trigger 111 forwardly so that the pivot pin 110 is located at the rear end of the slots 114 and is engaged within the offset portions 115 of said slots.

When the handle 85 is in its normal "up" position and the plunger 65 rests on the shock absorber 60, the parts are in the position shown in Fig. 1 of the drawing. When it is desired to operate the device, the handle 85 is depressed causing the handle to swing downwardly about the shaft 50. Link 95 is then pushed downwardly to

rotate the lever 101 in a clockwise direction about the pivot pin 100 to raise the link 106 and thus swing the trigger 111 in a clockwise direction about the pivot pin 110 to raise the plunger 65. As the plunger is raised, the pointed ends of the trigger slide upwardly and rearwardly along the under edges 70b of the hooks 70a. At a predetermined point in the vertical movement of the plunger, the pointed ends 116 move beyond the hooks and permit the compressed spring 72 to cause the plunger to descend and at the same time the driver blade will push out the foremost staple in the staple magazine. As the plunger descends the hook 70a will move down below the pointed ends 116. When the handle is released the trigger 111 will swing in a counterclockwise direction down with the upward movement of the handle.

The forward edges of the flanges 112 adjacent the pointed ends 116 are curved or cammed downwardly and rearwardly as at 117. As the cammed edges 117 contact the downwardly and forwardly curved or cammed edges 118 of the hooks 70b (see Fig. 3), the trigger 111 is pushed rearwardly against the tension of the torsion spring 109 so that the trigger will by-pass the hooks 70a. During such movement the shaft of the pivot pin 110 will move out of the offset portion 115 of the kidney shaped slot 114.

Elongation of the slot 114 permits the trigger to move back. However, as soon as the pointed end 116 passes below the hook 70a, torsion spring 109 will again snap the trigger forwardly and the pivot pin 117 will again snap into the offset portions 115 of the slots 114 and then the tacker will again be in the position shown in Fig. 1.

It will now be understood that the wing extensions 55 of the bottom stop resting on the edges 44 of the hardened front nose piece will permit said nose piece to take the shock caused when the plunger abruptly strikes the bottom stop. It will be noted furthermore, that the links and levers are relatively short so that they will withstand the strain of the operation. The lever is such that a small handle movement will permit a considerably large lift of the plunger. Furthermore, good leverage is obtained with a small handle movement. The tacker is easy to clean out and to assemble. The plunger is lifted centrally at its sides so that it is not likely to have any tilting movement which might cause a jam.

In Figs. 14 to 18 there is shown a tacker 10a embodying the invention and illustrating a modification. The tacker 10a is the same as the tacker 10 except for the differences noted herein-after.

The tacker 10a comprises a body 11, similar to the body 11 shown in Figs. 1 to 13. At the front of the body 11 is a nose piece 130 having a front wall 131 and side flanges 132 receiving the side walls of the body 11. The nose piece 130 may be hardened. The front wall 131 is formed with slots 39a similar to slots 39 to receive forwardly extending lugs 80 on the side wall 79 on staple magazine 78. Pivoted to the rear end of the staple magazine 78 on pivot pin 133 is a latch 134 having a hook 135 engaging pivot pin 81. The pivot pin 81 is preferably in the form of a removable bolt.

It will now be understood that upon removing the bolt 81 the staple magazine 78 as a whole may be slidably moved rearwardly to disengage the lugs 80 from the slots 39a and then the entire staple magazine may be withdrawn from the

75 tacker without disturbing the remainder of the tacker.

The side walls 132 of the nose piece may be formed with rearwardly extending ears 136 formed with through openings 137 serving as bearings for the transverse pivot pin 100 on which is mounted the lever 101. Since the nose piece is hardened, the apertured ears 136 provide a good long lasting bearing for the pivot pin 100.

In the tacker 10a the front wall 131 of the nose piece terminates at the upper end of the front edges of the side walls of the body 11. The handle 85a is similar to the handle 85 except that the side flanges 87 thereof contact the outer surfaces of the side walls of the body 11. Thus the pin 50 passes through bearing openings in the side walls of the body and in the side flanges of the handle, and the side flanges of the nose piece do not extend up to said pivot pin 50.

The plunger and the plunger actuating mechanism of the tacker 10a may be exactly similar to the plunger and plunger actuating mechanism of the tacker 10.

The handle 85a may be provided with a shock absorber 140. The shock absorber 140 comprises a rivet 141 passing through an opening in the top wall of the handle and through an opening in the wall 92. Contacting the underside of wall 92 is a rectangular rubber-like pad. Contacting the underside of said pad is a rectangular steel plate 144. The rivet 141 passes through registering openings in the pad 143 and plate 144. The side edges of the plate 144 overlie the upper edges of the side walls of the body 11 so that when the handle is depressed, the plate 144 will contact the top edges of the side walls of the body as shown in Fig. 18 to absorb the shock of depressing the handle.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, what I claim as new and desire to secure by Letters Patent of the United States, is:

1. A tacker comprising a body, a plunger mounted for sliding movement in the front end of the body, a handle mounted for pivotal movement on the body, a link pivoted at its upper end to depending means on the underside of the handle, a lever pivoted to the body and having a rearwardly extending arm pivoted to the lower end of the link, a second link pivoted at its upper end to a forwardly extending arm on said lever, a trigger pivoted at its rear end of the body, the lower end of the second link being pivoted to the trigger rearwardly of its forward end and forwardly of its pivot, said plunger being provided with hooks engageable by the forward end of the trigger upon pivotal movement of said lever.

2. The combination of claim 1, said trigger being formed with slotted openings to receive a pivot pin on the body to constitute said pivotal connection between the trigger and the body, and said slotted openings each having a downwardly extending offset adjacent its rear end to receive part of the pivot pin.

3. A stapler comprising a body having side

walls and being open at its front, a front nose piece fitted over the front of the body and having a front wall contacting the front edges of said side walls, and said nose piece having side walls contacting the side walls of said body, said side walls of the body being formed with through openings, a bottom stop having wings passing through said through openings, means to attach the front nose piece to the body, and the side walls of the front nose piece having portions supporting the undersides of said wings, a plunger mounted for sliding movement at the front end of the body, a handle mounted for pivotal movement on the body, said plunger being located above the bottom stop, spring means to depress said plunger into contact with the bottom stop, and means engageable with the plunger to raise said plunger upon pivotal movement of the handle, said last means including means to disengage the plunger when said plunger is raised to a predetermined height, to allow said spring means to depress said plunger against said bottom stop.

4. A tacker comprising a body open at its front and bottom, a nose piece fitted over the front of the body, means to attach the nose piece to the body, a staple magazine in the bottom, open end of the body, means to attach the rear end of the magazine to the rear end of the body, said staple magazine having at its front end a pair of forwardly extending lugs, and said nose piece being provided with a front wall formed with openings to receive said lugs to support the front end of the staple magazine, a plunger mounted for movement in the front end of the body, and means on the body to raise the plunger, and means to depress the plunger for driving staples from the front end of the magazine.

5. A tacker comprising a body, mounted for sliding movement, a plunger in the front end of the body, a handle mounted for pivotal movement on the body, a link pivoted at its upper end to depending means on the underside of the handle, a lever pivoted to the body and having a rearwardly extending arm pivoted to the lower end of the link, a second link pivoted at its upper end to a forwardly extending arm on said lever, a trigger pivoted at its rear end of the body, the lower end of the second link being pivoted to the trigger rearwardly of its forward end and forwardly of its pivot, said plunger being provided with hooks engageable by the forward end of the trigger upon pivotal movement of said lever, upon pivotally moving the lever downwardly toward the body to raise the plunger, and said trigger being disengageable from said hooks upon raising the plunger to a predetermined height, spring means to depress said plunger when it is released, spring means to raise the lever, and interengaging means on said plunger and trigger to cam the trigger rearwardly when the trigger moves down so as to permit the trigger to bypass said hooks and the plunger.

6. The combination of claim 5, in combination with a torsion spring about the pivotal connection about the forwardly extending arm of the lever and the upper end of the second link, said torsion spring being arranged to move the lower end of the second link forwardly for pulling the trigger forwardly beneath said hooks after said trigger has bypassed said hooks.

7. The combination of claim 6, said trigger being formed with slotted openings to receive a pivot pin on the body to constitute said pivotal connection between the trigger and the body, and said slotted openings each having a downwardly

extending offset adjacent its rear end to receive part of the pivot pin.

8. A gun type tacker comprising a body open at its front end, said body being formed with a hand hole, a front cover attached to the front end of said body, a handle pivoted to said body by means of a pin passing through registering openings in said handle, body and cover, spring means about said pin to raise the handle, said handle being depressible by a hand holding the tacker with the fingers of the hand inserted into said hand hole, a plunger mounted for sliding movement at the front of the body, spring means to depress the plunger, a link pivoted at its upper end to depending means on the underside of the handle, a lever pivoted mediate the ends thereof to said body, said lever having a rearwardly extending arm pivoted to the lower end of said link, and said lever having a forwardly extending arm, a second link pivoted at its upper end to the forward end of said forwardly extending arm, a transverse pin fixed on said body forwardly of the hand hole, a trigger formed at its rear end with a slot through which said last pin passes, the lower end of the second link being pivoted to said trigger, the said trigger having means at its front end engaging the plunger to lift the latter upon depressing the handle.

9. The combination of claim 8, in combination with a bottom stop below the plunger, said plunger being adapted to contact the bottom stop when depressed by the spring means which depresses the plunger, said bottom stop being formed with outwardly extending wings, said body having openings through which said wings pass and said front cover having portions engaging the undersides of said wings.

10. The combination of claim 9, in combination with a staple magazine, the bottom of the body being open, said magazine being located in the bottom open side of the body, means to attach the rear end of the magazine to the body, the front end of said magazine being provided with lug means, and said front nose piece being provided with openings to receive said lug means to support the front end of said staple magazine, and means to secure the front cover to the body at a point below the pivot pin which pivotally connects the handle to the body and cover.

11. A tacker comprising a body open at its front and bottom, a nose piece fitted over the front of the body, means to attach the nose piece to the body, a staple magazine in the bottom open end of the body, means to attach the rear end of the magazine to the rear end of the body, said staple magazine having at its front end a pair of forwardly extending lugs, and said nose piece being provided with a front wall formed with opening to receive said lugs to support the front end of the staple magazine, a plunger mounted for movement in the front end of the body, means on the body to raise the plunger, means to depress the plunger for driving staples from the front end of the magazine, a bottom stop for said plunger, said plunger being adapted to contact the bottom stop when depressed, said body having openings, said bottom stop having wings passing through said openings, and said front cover having edges contacting the undersides of said wings.

12. A tacker comprising a body formed with a hand hole, a nose piece at the front end of the body, said body and nose piece having registering openings, a pivot pin passing through said registering openings, a lever on said pin, a handle pivoted to the body, a bracket attached to the

underside of the handle, said lever having a rearwardly extending arm, a link interconnecting said bracket with said rearwardly extending arm, a plunger mounted in the body for sliding movement, a trigger pivoted to the body, said lever having a forwardly extending arm, a link interconnecting said forwardly connecting arm of the lever with said trigger, said plunger being formed with a hook, and said trigger having means to engage the underside of the hook to slide the plunger upon pivotal movement of said handle.

13. A tacker comprising a body, a nose piece attached to the front of the body, said nose piece having a front wall formed with a slot, a staple magazine in the body, means to attach the rear end of the magazine to the body, said magazine having a lug at its front end projecting through the slot to support the front end of the magazine.

14. A tacker comprising a body, a handle pivoted to the body, a shock absorber attached to the underside of the handle and comprising a compressible pad, and a plate contacting the underside of the pad, means to rivet said pad and plate to said handle, and said body having edges disposed below the sides of said plate whereby upon depression of the handle the sides of the plate will contact said edges.

15. A tacker comprising a body, mounted for sliding movement, a plunger in the front end of the body, a handle mounted for pivotal movement on the body, a link pivoted at its upper end to depending means on the underside of the handle, a lever pivoted to the body and having a rearwardly extending arm pivoted to the lower end of the link, a second link pivoted at its upper end to a forwardly extending arm on said lever, a trigger pivoted at its rear end of the body, the lower end of the second link being pivoted to the trigger rearwardly of its forward end and forwardly of its pivot, said plunger being provided with hooks engageable by the forward end of the trigger upon pivotal movement of said lever, a front nose piece mounted on the body, said front

nose piece being formed with apertured ears, and the same means for pivoting the lever to the body comprising a pivot pin passing through said apertured ears.

- 5 16. A gun type tacker comprising a body, said body being formed with a hand hole, a front cover attached to the front end of the body, a handle pivoted to said body, a plunger mounted for sliding movement at the front of the body, 10 a link, means including a pin to pivotally connect the upper end of the link to the underside of the handle, said front cover being formed with openings, a lever, a pivot pin at an intermediate portion of the lever journaled 15 in said openings in said cover, said lever having a rearwardly extending arm pivoted to the lower end of the link, and said lever having a forwardly extending arm, a second link pivoted at its upper end to the forward end of said forwardly extending arm, a transverse pin fixed on the body forwardly of said hand hole, a trigger formed at its rear end with a slot through which said last pin passes, the lower end of the second link being pivoted to said trigger, said trigger having means 20 at its front end engaging the plunger to lift the latter upon depressing the handle.

17. The combination of claim 16 in combination with a bottom stop below the plunger, spring means to depress said plunger downwardly into contact with said bottom stop, said front cover having portions engaging the undersides of said bottom stop to support the same.

MORRIS ABRAMS.
